[57] CLAIM

The ornamental design for a scraping device, as shown and described.

DESCRIPTION

FIG. 1 is a perspective view of a scraping device showing my new design;

FIG. 2 is a front elevational view thereof, the rear appearing identical;

FIG. 3 is a side elevational view thereof;

FIG. 4 is a top plan view thereof; and,

FIG. 5 is a bottom plan view thereof.

FIG. 1.

FIG. 2.

FIG. 3.

FIG. 4.

FIG. 5.
